UNITED STATES PATENT OFFICE.

HAROLD DE FOREST ARNOLD, OF EAST ORANGE, NEW JERSEY, ASSIGNOR TO WESTERN ELECTRIC COMPANY, OF NEW YORK, N. Y., A CORPORATION OF ILLINOIS.

GASEOUS REPEATER IN CIRCUITS OF LOW IMPEDANCE.

1,129,942.

Specification of Letters Patent. Patented Mar. 2, 1915.

Application filed May 28, 1914. Serial No. 841,568.

To all whom it may concern:

Be it known that I, HAROLD DE FOREST ARNOLD, a citizen of the United States, residing at East Orange, in the county of Essex and State of New Jersey, have invented certain new and useful Improvements in Gaseous Repeaters in Circuits of Low Impedance, of which the following is a full, clear, concise, and exact description.

10 This invention relates to the use of repeaters generally, and of vacuum discharge repeaters more particularly, as amplifiers without transformers.

Still more particularly, it relates to the use of thermionic repeaters for securing amplification of current in circuits of low impedance. By a thermionic current is meant current discharge from a hot cathode. Examples of thermionic repeaters are the 20 De Forest audion disclosed in Patent No. 879,532, dated February 18, 1914, and others, the Von Leiben & Riesz¹⁹¹⁸ repeater disclosed in Patent No. 1,038,910, dated September 17, 1912, etc. By vacuum discharge 25 is meant current discharge between electrodes in space from which nearly all atmosphere is exhausted. The expression vacuum discharge repeaters is intended to include repeaters of the thermionic types and 30 also those in which current flows between electrodes in space maintained in a conductive state by the arc or otherwise. The mercury arc repeater of an earlier application of this applicant, Serial No. 709,445, filed July 13, 1912, is an example of the class 35 of vacuum discharge repeaters but it is not of the thermionic type.

In many instances it is necessary or desirable, for securing the best results, to exclude 40 transformers from the circuit. Such is the case, for example, in those circuits in which the frequency is so low that efficient transformers are costly and difficult to design, as is the case in telegraph circuits in general 45 and especially in submarine and wireless telegraph circuits. It is particularly desirable to exclude transformers from circuits in which an exact reproduction of wave form is necessary for legibility, as, for ex-

ample, in submarine cable circuits. It is 50 also desirable to exclude transformers from circuits in which undistorted amplification must be secured over a wide range of frequencies, as, for example, in the reproduction of speech and music.

55

Heretofore it has been necessary to employ transformers in circuit with the audion in order to secure efficient amplification of current by the audion, and this is especially true where the amplification is desired in 60 circuits of low impedance. This is due to the fact that the impedance of the input circuit of an efficiently operating audion is very high, at least 100,000 ohms and in general as high as 10 megohms. Hence, in a 65 circuit of low impedance, if no transformer is used, the larger part of the possible current amplification by the audion is lost. For example, if the impedance of the input circuit of the audion is only 100,000 ohms and 70 the input circuit of the audion be connected, without the use of transformers, in a line of 1000 ohms impedance, at least 90% of the possible current amplification is lost. Moreover, in the case of audions of the prior art, 75 the impedance in the output circuit of the audion is always so great that a considerable additional loss of possible amplification must occur if the output circuit of the audion is directly connected to a circuit of 80 low impedance.

It has been discovered that audions of the usual type may be so constructed that, without the use of transformers, they will step up the input voltage of either direct current 85 or alternating current of any frequency in one step to as much as 30 times its original value, or in two successive steps to as much as 500 times its original value. The voltage amplification thus secured is entirely 90 free from wave distortion whatever may be the initial frequency and wave form. This type of audion will, for convenience, be hereinafter referred to as the high-voltage output audion.

95

It has furthermore been discovered that audions may be constructed which will step down the input voltage, for example, to one.

third of its original value. This last mentioned type of audion has a high current and a low voltage output. Because of its low output impedance, such type of audion 5 can be worked efficiently into a line of like impedance. This new type of audion will, for convenience, hereinafter be referred to as the high-current output audion.

The structures which will provide the 10 greatest degree of efficiency in the above mentioned different types of audions form the subject-matter of a copending application in my name, Ser. No. 841,567 filed of even date herewith.

15 It has been discovered that a combination of one or more of the aforementioned high-voltage output type of audions working into one of the high-current output type, will operate, without transformers, from a line of 20 low impedance, for example, 250 ohms, into a like line with a resultant current much greater, fifty or more times greater, than would flow in the second circuit if it were directly connected to the first circuit. The 25 present invention is directed to such combination of two different types of repeaters, preferably audions. A system designed to secure the same result and employing a large number of the high-voltage output 30 type of audions connected in multiple and working into a common output circuit in lieu of a single audion of the high-current output type, forms the subject-matter of still another application for patent in my 35 name, Ser. No. 841,569 filed of even date herewith.

The present invention may be more readily understood by reference to the accompanying drawings in which—

40 Figure 1 is a view in perspective of an audion of the high-voltage output type; Fig. 2 is a similar fragmentary view of an audion of the high-current output type; Fig. 3 is a similar fragmentary view of the 45 two different types of audions embodied in a unitary structure; Fig. 4 shows a circuit arrangement embodying this invention in which a plurality of audions of the high-voltage type in tandem work into an audion 50 of the low-voltage type; Fig. 5 shows a simplified circuit arrangement giving the same result as in Fig. 4; Fig. 6 shows a still further modification more particularly applicable to telephone circuits; Fig. 7 shows a plurality of audions of the high-voltage type in 55 tandem working into a plurality of audions of the high current output type, each of the latter feeding into a separate output line; and Fig. 8 shows a circuit arrangement embodying the invention in which the two different types of audions are combined in one 60 bulb.

Like reference characters refer to like parts throughout the several views.

In the drawings, the audions 1 are of the 65 high-voltage output type and the audions 2 are of the high-current output type. In the former type, the input electrode may be in the form of a grid, preferably made of very fine wire with a fine mesh or the like, and 70 the output anode or plate 4 is placed at a considerable distance from the cathode which is preferably a filament 5, as shown. The filament need not present a large active area. The filament, grid and plate are as 75 usual sealed in an evacuated bulb 6. In order to secure best results in this type of audion, the grid should be near the filament, the plate should be distant from the filament, and the grid should present a finely 80 meshed or discontinuous surface between the filament and the plate.

In the high-current output type of audion, the input electrode or grid 7 may be at any side of the filament and should have a coarse 85 mesh or preferably consist merely of a short length of wire. The output electrode or plate 8 is placed as near to the filament 9 as is conveniently possible. The filament preferably presents a large, active area. The 90 filament, grid and plate are as usual sealed in an evacuated bulb 10. In order to secure the best results in this type of audion, the grid and plate should both be near the filament, the filament area should be large, 95 and the grid should present the least possible obstruction between the filament and plate.

As hereinbefore stated, the high-voltage output type of audion gives an amplification 100 with low current and high voltage in its output circuit; whereas the high-current output type gives amplification with high current and low voltage, and hence low impedance, in its output circuit.

In Fig. 4, two high-voltage output audions 1, 1 connected in tandem are shown working into a high-current output audion 2. The batteries 11 are preferably of such value as to make each of the grids 3, 3 and 7 normally about five volts negative with respect to its adjacent filament. The several filaments are heated by the respective batteries 12. The output circuit of each audion includes its plate, a high resistance 14, a 115 battery 13 and the filament of the audion. The resistance 14 should be, for example, 100,000 ohms or more. The input circuit of the first audion of the group is directly connected to the input line 15. The input voltage on the grid of the first audion 1 causes an increase in the voltage of the current flowing in the output circuit of said audion, thereby developing a voltage change on the grid of the next audion of the series, and so 120 on. As a result of such construction and arrangement of these audions, the voltage in the input circuit of the second of the two 125

audions in tandem is much greater than that impressed upon the first, although the current in the interconnecting circuit is small. The audion 2 acts as an amplifier in which the current is increased and the voltage lowered in its output circuit. Because of the fact that the impedance in the output circuit of the audion 2 is lowered, it can be worked efficiently into a line 16 of low impedance. It has been found, for example, that the amplifying means shown in Fig. 4 will work from an incoming line of 250 ohms impedance into an outgoing line of like impedance with a resultant current of more than fifty times that which would flow in the outgoing line if the latter were directly connected to the incoming line.

Fig. 5 shows a simplification of the system illustrated in Fig. 4, in that a common battery 12 furnishes current to all the filaments, said filaments being connected in series with the battery, and a common battery 13 serves for all of the plates.

Fig. 6 shows a further simplification of the system illustrated in Fig. 5. An impedance coil 17 is included in bridge of the output circuit of each audion, and in the output circuit of the two audions 1, 1, condensers 18, 18 are inserted in series with the resistances 14. By such arrangement the several batteries 11 may be largely reduced in voltage. This arrangement is particularly applicable to embodiment in a telephone system.

Fig. 7 shows a plurality of the high-voltage output audions in tandem working into a plurality of the high-current output audions, each of the latter working into its own output circuit 19, 20 or 21. Otherwise, the circuit arrangement is substantially that shown in Fig. 5. The arrangement shown in Fig. 7 is particularly applicable to the operation of several loud-speaking receivers from a common talking circuit.

Fig. 8 shows a structure and circuit arrangement in which an audion of the high-voltage output type works into an audion of the high-current output type, the two audions being contained in a single bulb and operating from a common filament having one branch 5 for the audion 1 and another branch 9 for the audion 2. The input electrode 7 of the audion 2 is shown in the form of a short length of wire. The circuit arrangement is substantially that illustrated in Figs. 4 and 5, and further description thereof is deemed unnecessary. This structure and arrangement have been found to operate successfully, without the interposition of transformers, between lines of the impedance of ordinary telephone lines.

As applied to submarine cable work for amplifying the feeble current at the receiving end the invention is of special import-

tance. The large amplification attained 65 makes it possible to operate over such cables at greatly increased speed. Furthermore, less delicate recording devices will suffice as a substitute for the ordinary siphon recorder. Moreover, the high amplification 70 secured renders possible the direct repetition from one section of a cable to another or from submarine to land telegraph lines. The invention is also particularly adapted for use in circuits where especially pure, 75 loud reproduction of speech or music is desired. In general in the art of submarine, land and wireless telegraphy, the invention is of importance with reference to recording, high-speed working and direct repetition 80 from one type of system to another type of system.

What is claimed is:

1. The combination with a source of feeble electric currents, of a thermionic repeater having an input circuit directly connected to said source of current and an output circuit of high voltage, and a second thermionic repeater having an output circuit of low impedance and having an input circuit directly connected to the output circuit of said first mentioned repeater.

2. The combination with a plurality of thermionic repeaters connected in tandem, the first repeater of the series having a high-voltage output and the last repeater of the series having a high-current output.

3. The combination with an incoming and an outgoing line of low impedance, of a plurality of thermionic repeaters in tandem, the first of said repeaters having a high-voltage output and the last of said repeaters having a high-current output, and the first of said repeaters having its input circuit directly connected to said incoming line, and the last of said repeaters having its output circuit directly connected to said outgoing line.

4. The combination with a line of low impedance, of a current amplifying means directly connected therewith, said amplifying means comprising a plurality of thermionic repeaters in tandem, the first of said repeaters having a high-voltage output and the last of said repeaters having a high-current output.

5. The combination with a repeater, of a plurality of vacuum discharge repeaters connected in multiple with the output circuit of said first mentioned repeater, said mentioned repeater having a high-voltage output and said other repeaters each having a high-current output.

6. The combination with a thermionic repeater, of a plurality of thermionic repeaters connected in multiple into which said first mentioned repeater works, said first mentioned repeater having a high-voltage

output and said other repeaters having a high-current output.

7. The combination of two thermionic repeater structures connected in tandem and having a common inclosing bulb, the first of said structures having a high-voltage output and the other a high-current output.

In witness whereof, I hereunto subscribe my name this 25 day of May, A. D. 1914.

HAROLD DE FOREST ARNOLD.
